UNITED STATES PATENT OFFICE.

EDWARD W. BURGESS, OF CHICAGO, ILLINOIS, ASSIGNOR, BY MESNE ASSIGNMENTS, TO INTERNATIONAL HARVESTER COMPANY, A CORPORATION OF NEW JERSEY.

PITMAN CONNECTION.

1,334,518.

Specification of Letters Patent. Patented Mar. 23, 1920.

Application filed July 5, 1916. Serial No. 107,680.

To all whom it may concern:

Be it known that I, EDWARD W. BURGESS, a citizen of the United States, residing at Chicago, in the county of Cook and State of Illinois, have invented certain new and useful Improvements in Pitman Connections, of which the following is a full, clear, and exact specification.

My invention relates to pitman connections, and is adapted in particular for connecting the pitman of a mower with a spherical bearing block carried by the knife head, wherein a pair of elastic straps secured to the body of the pitman are provided with complementary saucer-shaped depressions forming bearing members adapted to operatively receive the spherical bearing block between them; the object of the invention being to provide releasable spring-pressed means carried by the pitman and operative to securely hold the straps in engagement with the bearing block, and to automatically prevent any destructive loosening of the bearing parts relative to each other due to wear in the operation of the machine; the securing means being easily released when it is desired to disconnect the parts.

I attain this object by means of the mechanism illustrated in the accompanying drawing, in which—

Figure 1 is a top plan view of part of a mower pitman embodying my invention;

Fig. 2 is a side elevation of Fig. 1; and

Fig. 3 is a vertical cross section of Fig. 2 on an enlarged scale taken on line 3—3 of Fig. 2 and looking in the direction of the arrow points.

Referring to the drawings, wherein the same reference characters designate like parts throughout the several views, 4 represents the body of the pitman, preferably made of wood, 5 a pitman strap secured to the front side thereof, 6 a complementary strap secured to the rear side of the pitman, the straps being secured to the body of the pitman by means of rivets 7, and extending beyond the end thereof are provided with saucer-shaped bearing members 8 adapted to partially receive a spherical bearing block 9 forming part of a knife head (not shown). The straps have sufficient elasticity to permit them to spread apart in connecting or

disconnecting them with or from the bearing block.

The means for securing the bearing parts in operative relation include a vertically disposed arm 10, having oppositely disposed trunnion members 11 at its lower end that are journaled in the pitman straps, and coaxially curved fingers 12 spaced apart transversely of the straps and adapted to receive said straps between them. The inner surfaces of the fingers are inclined outward and downward toward their lower ends and are adapted to slidably engage with raised inclined bosses 13 on the straps adjacent the bearing members in a manner to control the position of the straps relative to the bearing blocks. 14 represents a laterally extending ear member upon the end of the body portion of the strap 5 and provided with an opening that slidably receives the reduced portion of a link 15, that is provided with an enlarged threaded portion 16 near its middle receiving an adjusting nut 17. The link then turns upward and laterally, and its hook-shaped end 18 is received by an opening in the upper end of the arm 10 and is retained therein by means of a cotter pin 19. 20 represents a compression spring encircling the body of the link 15 and reactive between the adjusting nut 17 and the ear member 14 in a manner to normally swing the arm 10 in a direction to throw the fingers 12 into engagement with the bosses 13 upon the pitman straps and thereby secure the coacting bearing members in operative relation and automatically prevent any loosening of the connected parts due to wear.

The upper end of the arm 10 is provided with a curved shoulder portion 21 adapted to receive the thumb of an operator, whose fingers grasp the lower sides of the pitman straps, and pressure may then be applied in a direction to move the fingers 12 from engagement with the bosses 13 and permit a quick connection or disconnection of the pitman with or from the bearing block of the knife head.

Having shown and described one form that my invention may assume in practice, I do not desire that it be confined to the specific details of the structure as illustrated, it being understood that changes may be made in the form, proportion and organiza-

tion of its associated parts without departing from the spirit of the invention as indicated in the scope of the appended claims.

What I claim as my invention, and desire to secure by Letters Patent, is:

1. In a pitman connection, a pitman having a pair of straps, one of said straps being resilient, means including a member pivoted to said pitman for pressing said straps toward each other, and longitudinally reciprocal resiliently actuated means for forcing said pivoted member in a direction to actuate said straps toward each other.
10. 2. In a pitman connection, a pitman having a pair of straps, one of said straps being resilient, means including a member pivoted to said pitman for forcing one of said straps toward the other strap, and reciprocal means for resiliently actuating said pivoted member.
15. 3. In a pitman connection, a pitman having a pair of straps, one of said straps being resilient, means for pressing one of said straps toward the other strap, said means including an arm pivoted to said pitman and having an inclined finger adapted to coöperate with one of said straps, and reciprocal spring actuated means for actuating said pivoted member.
20. 4. In a pitman connection, a pair of elastic straps having bearing members thereon, and means for pressing said straps toward each other, said means including an arm pivotally connected with said straps and provided with spaced inclined fingers slidably engaging therewith.
25. 5. In a pitman connection, a pair of elastic straps having bearing members thereon, means for pressing said straps toward each other, said means including inclined bosses upon the sides of said straps, and an arm pivotally connected with said straps and provided with inclined fingers spaced apart and adapted to operatively engage with said inclined bosses.
30. 6. In a pitman connection, a pair of elastic straps having bearing members thereon, means for pressing said straps toward each other, said means including a spring-pressed arm pivotally connected with said straps and provided with inclined fingers spaced apart and slidably engaging therewith.
35. 7. In a pitman connection, a pair of elastic straps having bearing members thereon, means for pressing said straps toward each other, said means including an arm having one end thereof pivotally connected with said straps, a spring-pressed link slidably mounted on one of said straps and operatively connected with the opposite end of said arm, said arm being provided with coaxially curved fingers spaced apart and slidably engaging with said straps.
40. 8. In a pitman connection, a pair of elastic straps having bearing members thereon,

means for pressing said straps toward each other, said means including a vertically disposed arm pivoted between said straps, coaxially curved inclined fingers carried by said arm and engaging with said straps, and a pressure spring reactive to normally turn said arm in a direction to press said bearing members toward each other.

9. In a pitman connection, a pitman body, a pair of elastic straps secured thereto and extending beyond the end thereof and provided with bearing members, means for pressing said bearing members toward each other, said means including a vertically disposed arm provided with oppositely disposed trunnions upon its lower end whereby said arm is pivotally mounted upon said straps, coaxially curved fingers carried by said arm and engaging with the extended ends of said straps, and a spring-pressed link slidably mounted upon one of said straps and operatively connected with the upper end of said arm.

10. In a pitman connection, a pitman having a pair of straps one of which is resilient, and means movable transverse to the longitudinal axis of the pitman and adapted to receive said straps for forcing said resilient strap toward the other strap.

11. In a pitman connection, a pitman having resilient straps, and means movable transverse to the longitudinal axis of said pitman and embracing said straps for forcing said straps toward each other.

12. In a pitman connection, a pitman having resilient straps, and means pivoted to said pitman and movable transverse to the longitudinal axis thereof and engaging said straps for forcing said straps toward each other.

13. In a pitman connection, a pitman having resilient straps, and means pivoted to and movable transverse to the longitudinal axis of said pitman and engageable with the outer surfaces of said straps for forcing said straps toward each other.

14. In a pitman connection, a pitman having resilient straps, and means having cam fingers engageable with each of said straps and movable transverse to the axis of said straps for forcing the straps toward each other.

15. In a pitman connection, a pitman having resilient straps, and means pivoted to, and having cam surfaces engageable with each of said straps, for forcing the straps toward each other.

16. In a pitman connection, a pitman having resilient straps, and a member movable across and engageable with the outer surfaces of said straps for forcing the straps toward each other.

17. In a pitman connection, a pitman having resilient straps, and a member having cam surfaces movable across and engageable

with the outer surfaces of said straps for forcing said straps toward each other.

18. In a pitman connection, a pitman having a pair of resilient straps, and means pivoted to and engageable with said straps for forcing said straps toward each other.

19. In a pitman connection, a pitman hav-

ing a pair of resilient straps, said straps having bearing surfaces thereon, and means pivoted to said pitman and engageable with said surfaces for forcing said straps toward each other.

In testimony whereof I affix my signature.
EDWARD W. BURGESS.
